CONDUIT-DISCHARGE MEANS

Paulsen Spence, Baton Rouge, La.

Application March 10, 1954, Serial No. 415,258

5 Claims. (Cl. 302—63)

My invention relates to materials-handling equipment, as for the separation and accumulation of sand to the exclusion of water, in the case of a water suspension of sand.

It is an object of the invention to provide improved means of the character indicated.

It is another object to provide an improved materials-handling construction in which a heavy suspension in a liquid may be accumulated in a more uniformly spread pile sloping away from the point of discharge.

It is also an object to provide a conduit-discharge device to promote accumulation of a sand pile immediately adjacent a backstop or retaining wall, without eroding the backstop or any accumulations between the pile and the backstop.

It is a further object to provide a relatively simple discharge device lending itself to connection to available conduits.

Other objects and various further features of novelty and invention will be pointed out or will occur to those skilled in the art from a reading of the following specification in conjunction with the accompanying drawings. In said drawings, which show, for illustrative purposes only, preferred forms of the invention:

Fig. 1 is a side view, partly in section, illustrating a conduit-discharge member incorporating features of the invention and schematically indicating how a solid pile accumulation may be promoted through the use of the device; and

Fig. 2 is a fragmentary side view of a modification.

Briefly stated, my invention contemplates the application of an abrupt flow-terminating and flow-reversing chamber at the end of a discharge conduit for the handling of heavy solid suspensions in water or other fluid; my reversing chamber promptly discharges the suspension after having reversed the flow. In the case of sand suspensions in water, as customarily encountered in gravel and sand-dredging operations, the water will push the sand, so that, when discharged into a sand pile, the water and sand run-off backs up and erodes the backstop or any accumulations between the point of discharge and the backstop. On the other hand, with my invention, I achieve such flow reversal that the sand tends to be discharged, to settle, and to accumulate essentially "uphill" from the water, and the run-off water and sand will spread uniformly away from the point of discharge, thus creating a substantially uniform gradient sloping away from the backstop, and leaving the backstop intact.

Referring to Fig. 1 of the drawings, my invention is shown in application to a conduit-discharge member 5 applied as a terminal fitting to an open flume or trough 6 constituting the discharge end of a sand or the like processing establishment. The device 5 may comprise essentially a chamber 7 of effective cross-sectional area preferably substantially exceeding that of the inlet or supply flume 6. In the form shown, the supply flume 6 is semi-cylindrical, and the peripherally continuous na-

ture of the chamber 5 is conveniently established by merely seam-welding at 8 a relatively short inverted length of the flume material over the end of the flume 6 as shown. In order to stop and reverse flow, I close the downstream end of the chamber 7, as at 9, and provide a transversely or downwardly extending discharge outlet 10 communicating with the downstream end of the chamber 7. The discharge outlet 10 is preferably of substantially the effective cross-sectional area of the chamber 7, and I have shown it as a tubular member welded at 11 to chamber 7 and braced by brackets or gussets 12 at both sides of the inner corner of the joint between members 7—10. The angle between the inlet-flow axis and the discharge axis in outlet 10 is preferably an acute angle, as shown.

In use, a strong flow of sand or the like suspended in water or other fluid may be passed continuously down the flume 6 and reversed in fitting 5 for discharge through the outlet 10. The construction will cause flow reversal, as suggested by the arrow 13, with the result that the predominant body of water is discharged below the predominant body of sand. Resulting direct water run-off is suggested by the arrow 14. The sand pile will tend to accumulate as suggested by the profile 15, without noticeable loss of sand through the water run-off and, if desired, a fill close against a backstop or wall 16 may be achieved. The slope of the fill away from the backstop will depend upon the amount of sand in the water and on the flow rate, and slopes much more gradual than that shown in the drawing may be achieved. The slope of this type of fill contrasts sharply with that of the sand-pile profile 17, which is ordinarily obtained through direct discharge of the sand suspension without flow reversal.

If it should develop that the flow transiently becomes predominantly water, with relatively little sand suspension, there may be a substantial increase in flow rate, causing possibly excessive reaction thrust at wall 9; to offset such excessive thrust development, I provide a relief opening in the lower end of chamber 5, as at 19, functioning to bypass excessive water flow. Opening 19 is relatively small compared to the cross-sectional area of chamber 9; therefore, chamber 9 may nevertheless be said to be effectively closed.

In Fig. 2, I show a construction which may, in substantially all respects, resemble that described in Fig. 1, and therefore corresponding parts have been given the same reference numerals. The only difference in the construction of Fig. 2 is that the inlet 20 to the chamber 7 is so formed, as with a standard pipe flange 22, as to accommodate removable attachment to a closed conventional conduit 23.

It will be seen that I have described an extremely simple construction lending itself to use in any application in which solid suspensions in fluids are continuously discharged. The invention is applicable to closed-pipe and to open-trough or flume discharges, without in any way interfering with the continuous flow of discharge materials. A sand pile may be accumulated right up to a backwall as shown; or, if the backstop happens to be a bulldozed local pile of sand, a fill can still be made adjacent the bulldozed pile, without eating away the bulldozed pile.

While I have described the invention in detail for the preferred forms shown, it will be understood that modifications may be made within the scope of the invention as defined in the following claims.

I claim:

1. In combination, a downwardly inclined open flume for accommodating a continuous flow of liquid containing relatively dense solids suspended therein, a pe-

peripherally continuous body axially aligned with and connected to the lower end of said flume, said body having an effective cross-sectional area substantially exceeding that of the flow in said flume, means effectively closing the downstream end of said body, and a short downwardly and rearwardly directed discharge tube communicating with the downstream end of said body and having an effective cross-sectional area substantially exceeding that of the flow in said flume, whereby flow of liquid and solid suspension may be reversed and the discharged solid may pack highest near the location of discharge, while the liquid may run off, with minimum solid suspension, in the general direction of flow in said flume.

2. The combination according to claim 1, in which said discharge tube is of a cross-sectional area approximating that of said body.

3. The combination of claim 1, in which a bypass opening is provided in the upper part of the downstream end of said body.

4. In combination, downwardly inclined conduit means accommodating a continuous flow of liquid with relatively dense solids suspended therein and carried therewith, closure means substantially closing the lower end of said conduit means said last-defined means having an effective

5
10
15

cross-sectional area substantially exceeding that of the flow upstream from said end, a relatively short discharge nozzle communicating with the lower end of said conduit means and discharging downwardly and rearwardly in the sense of flow down said conduit means and also having an effective cross-sectional area substantially exceeding that of the flow upstream from said end, whereby the liquid and solid flow may be reversed, so that discharged solid distribution away from the vicinity of the point of discharge may develop a gradual downwardly inclined bank over which the liquid may freely run off without cutting the bank.

5. The combination of claim 4, in which said closure means at said lower end is an enlarged chamber.
